UNITED STATES PATENT OFFICE

2,199,836

AUXILIARY FIREPLACE HEATER

Thomas Mairs, Tacoma, Wash.

Application July 11, 1939, Serial No. 283,797

4 Claims. (Cl. 237—51)

This invention relates to means for utilizing the otherwise waste heat of the smoke of the ordinary heating furnace, boiler, or other heat-developing apparatus, and has for its objects, first, to provide a means connected to the smoke chimney for extracting the heat of the rising smoke or waste gases therein as it passes through the device; second, to provide an apparatus for heating the air of a room by means of the hot gases in the chimney; third, to combine said air-heating means with an open fireplace; fourth, to provide a suitable control means whereby the apparatus may be placed in or out of action; and fifth, to provide such an apparatus as will be simple and cheap in construction, permanent in nature, and effective in use.

I attain these and other objects by the devices and arrangements illustrated in the accompanying drawing, in which,

Fig. 1 is a vertical section of my improved auxiliary fireplace heater, taken on the line 1—1 in Fig. 2; Fig. 2 is a horizontal section thereof taken on the line 2—2 in Fig. 1; Fig. 3 is a vertical section of a portion thereof taken on the line 3—3 in Fig. 2; Fig. 4 is a horizontal section of a variation of my invention in which the heat from the chimney is used in a room without a fireplace; and Fig. 5 is a vertical section thereof.

Similar numerals of reference refer to similar parts throughout the several views.

Referring to Fig. 1 of the drawing, it will be seen that the furnace, boiler, or other heat-generating apparatus 6 is located, as is customary, in the basement of the building, and is provided with a smoke pipe 7 which leads therefrom through the chimney walls 8 and into the vertical smoke flue 9 thereof. It will also be seen by Figs. 2 and 3 that this flue 9 is positioned towards the rear and to one side of the fireplace located on the floor above.

In the preferred form of my invention, the fireplace is one of the type known as "heat circulators" which, normally, are provided with a hearth 10 having a metal back plate 11 and metal side plates 12, both adapted to transmit the radiated and conducted heat from the fire on the hearth 10 to the air chamber 13 surrounding the rear and sides of the hearth. The gases of combustion eventually pass to the chimney flue 14 by the passage 15. This air chamber 13 is connected to the room 16 by means of suitable cold air passages 17 positioned, usually, near the floor or base of the hearth 10. The air in the said space 13 is therefore heated by the fire on the hearth 10

and passes out into the room 16 by means of suitable hot air passages 18. The air chamber 13 is provided with a back closure plate 19 and side closure plates 20. In my apparatus the side closure plates 20 are connected to outer enclosing plates 21 which form a second confined chamber which I have designated as the smoke chamber 22.

The chimney flue 9 is provided with an opening 23 through the wall thereof and connecting with an opening 24 through the said outer plate 21 of the smoke chamber, near the bottom thereof, and also the said flue 9 is provided with a second or upper opening 25 connecting with an upper opening 26 through the said outer plate 21. The smoke chamber 22 is provided with a baffle plate 27, positioned between the lower opening 24 and the upper opening 26 (Fig. 3) to force the hot gases from the chimney flue 9 to circulate within the smoke chamber and to contact as large an area of the back and side closure plates 19 and 20 as is practical.

A pair of control plates or valves are mounted in the wall openings 24 and 26 (Fig. 3). The lower valve plate 28 is hinged at its upper end 29 to the plate 21 and extends into the flue 9 through the opening 23, while the upper valve plate 30 is hinged at its lower end 31 to the said plate 21 and also extends into the flue 9 through the opening 25. These two plates 28 and 30 are adapted to substantially close their respective openings or to swing into the flue 9 to divert the hot gases flowing upward therein into the smoke chamber 22 and then guide them from the said smoke chamber 22 into the flue 9 again.

In order to facilitate the operation of these two plates 28 and 30 they may be connected together in such manner as to balance each other by providing the upper plate 30 with an arm or lever 32 and connecting said lever 32 with the complementary position on the lower plate 28 by means of a link 33. Since the link 33 connects the two plates on opposite sides of the respective hinges 29 and 31, and since the points of connection are complementary to each other, or equally distant from the said hinges, it is evident that they will balance each other in all positions and that the operation of one will cause the other to move equally in the opposite direction. Suitable operating means, not shown, may be provided whereby they may be controlled from the room 16.

A modified form of my invention is shown in Figs. 4 and 5 in which the heat of the waste gases flowing up the chimney flue is extracted and

used to heat a room without any fireplace. In this case the chimney flue 9 is cut and a metal radiator chamber is inserted therein. This radiator chamber comprises an inner open-ended 5 smoke chamber 50 through which the smoke and hot gases in the chimney pass upward. The walls 51 of this chamber 50 may be provided with a series of inward extending fins or plates 52 secured thereto. These fins 52 are surrounded by 10 the flowing hot gases and conduct the heat therefrom to the walls 51, thus increasing the area of the surfaces exposed to the heat. The walls 51 of this smoke chamber 50 are surrounded by a closed metal air chamber 53, having a cold air 15 inlet grid 54 at the base and a hot air outlet grid 55 at the top. The air inlet 54 is preferably positioned at the floor of the room 56, thus taking the cold air therefrom and delivering warm air to the room at a higher level.

20 It is, of course, understood that many variations may be made in the details of my improved auxiliary heater without departing from the spirit of my invention as outlined in the appended claims, and that the words and terms 25 used in the specification and claims have been selected for convenience of description and are to be given the most generic meanings consistent with the present art.

Having, therefore, described my invention,

what I claim and desire to secure by Letters Patent, is:

1. An auxiliary heater comprising an open fireplace having metal walls; an air chamber having metal walls, at least one such wall being common 5 to said air chamber and said open fireplace; air inlet and outlet passages to said air chamber; a flue in which hot waste gases are passing; a smoke chamber having metal walls, at least one wall of which is common to said smoke chamber 10 and said air chamber; and passages connecting the lower and upper portions of said smoke chamber to said flue and forming inlet and outlet connections for the hot gases therein.

2. An auxiliary heater as set forth in claim 1, 15 together with means directing the hot gases to pass from said flue through said smoke chamber and return to said flue.

3. An auxiliary heater as set forth in claim 1, 20 together with controllable means directing the hot gases to pass from said flue through said smoke chamber and return to said flue.

4. An auxiliary heater as set forth in claim 1, 25 together with a baffle plate in said smoke chamber and positioned between the upper and lower passages and adapted to force the smoke to circulate in said smoke chamber in passing from the inlet to the outlet passages thereof.

THOMAS MAIRS.
